US0D1003192S

(12) **United States Design Patent** (10) **Patent No.:** **US D1,003,192 S**
(45) **Date of Patent:** **** Oct. 31, 2023**

(54) **BUCKLE**

(71) Applicant: **Duraflex Hong Kong Limited**, Hong Kong (CN)

(72) Inventor: **Yick Fai Chan**, Hong Kong (CN)

(73) Assignee: **DURAFLEX HONG KONG LIMITED**, Hong Kong (CN)

(**) Term: **15 Years**

(21) Appl. No.: **29/721,027**

(22) Filed: **Jan. 17, 2020**

(51) LOC (14) Cl. **02-07**

(52) U.S. Cl.

USPC **D11/216**

Assistant Examiner — Heather Wencl

(74) Attorney, Agent, or Firm — Collard & Roe, P.C.

(57) **CLAIM**

The ornamental design for a buckle, as shown and described.

DESCRIPTION

FIG. 1 is a top, front and left side perspective view of a buckle, showing my new design;

FIG. 2 is a top view thereof;

FIG. 3 is a bottom view thereof;

FIG. 4 is a left side view thereof;

FIG. 5 is a right side view thereof;

FIG. 6 is a front view thereof; and,

FIG. 7 is a rear view thereof.

The features shown in broken lines show portions of the buckle that form no part of the claimed design.

1 Claim, 3 Drawing Sheets
